(57) CLAIM

I claim the ornamental design for a bottle, as shown and described.

DESCRIPTION

FIG. 1 is a front perspective view;
FIG. 2 is a front view;
FIG. 3 is a partial bottom perspective view;
FIG. 4 is a top view; and,
FIG. 5 is a bottom view.

The dot-dash broken line(s) in the drawings define the bounds of the claim and form no part thereof.
